[57] CLAIM

The ornamental design for an athletic glove for golf, tennis, baseball and racquetball, as shown.

DESCRIPTION

FIG. 1 is a plan view of the back of the athletic glove for golf, tennis, baseball and racquetball as worn showing
my new design;

FIG. 2 is a perspective view of the palm side thereof;
FIG. 3 is a top plan view of the athletic glove for golf,
tennis, baseball and racquetball of FIG. 1 folded flat;
and

FIG. 4 is a bottom plan view of the athletic glove for golf, tennis, baseball and racquetball of FIG. 1 folded flat.
